LEG PROSTHESIS**Felix Kleinekathöfer, Endorf, Upper Bavaria, Germany****Application February 2, 1954, Serial No. 407,782****Claims priority, application Germany February 3, 1953****5 Claims. (Cl. 3—27)**

This invention relates to a leg prosthesis, especially a leg prosthesis which is equipped with a pressure-controlled knee-joint brake.

As far as the control of the movements of an artificial leg during use is concerned, my Patent No. 2,588,013, March 4, 1952; is concerned with a portion only of the whole range of operation, namely, that during which the leg is moved into contact with the ground and, thus, is placed under pressure.

My present invention aims at the control of the operation of a leg prosthesis within the rest portion of the functions of the leg. More specifically, my invention has for one of its objects the control of the use of the leg prosthesis during the swinging motions of the shank of the leg.

With my invention applied to the artificial leg of the above referred to patent, it will be possible to control the whole range of possible functions.

While suggestions have already been made to eliminate or at least to lessen the danger of unintended bending or of a collapse of knee-joints when pressure is applied, the known artificial legs still have serious disadvantages which make themselves particularly felt when the leg is out of contact with the ground, that is, during the forward swinging movement of the shank. These shortcomings influence the entire sequence of movements and even the condition during the application of pressure. The main difficulty consists in the fact that at the beginning of the swinging action when the artificial limb, with no pressure or load applied, is swung forward, the shank, due to its weight and inertia, does not follow the forward movement of the thigh fast enough for normal walking. As a consequence, the shank and foot remain too far behind, causing the knee-joint to bend through an excessive angle, which makes the movement of the leg appear unnatural. It has also been suggested to reduce the undesired movement of the shank by locating the center of rotation of the knee-joint so that the center of gravity of the shank is moved forwardly, or by providing elastic webbing or springs to favor the outstretched position of the leg in the knee-joint.

The known devices to minimize the undesirable shank movement, and especially the known elastic members used for this purpose, have the disadvantage of acting too strongly in the first phase of the swinging movement and too weakly in the second phase. The same is true for the mentioned shift of the center of gravity of the shank. It with the known devices the swinging movement is adjusted for a certain moderate walking pace, such adjustment is no longer correct when the wearer of the artificial leg increases or reduces the rate of movement. If he, for instance, slows down, the shank will move forward too strongly and will hang stiffly from the knee-joint. If, on the other hand, the walking speed is increased above the average, the shank will not move forward fast enough to support the load of the body, so that the knee-joint may collapse and the wearer may drop to the ground.

2

The primary object of my invention is to overcome the above referred to disadvantages and to provide, as has already been indicated, a leg prosthesis having an improved control mechanism for the swinging movements of the leg.

Other objects of the invention center about an artificial leg having a mechanism as referred to, which will reliably control the forward motion of the shank during walking regardless of the speed of walking, which will cause the shank to swing easily and naturally within the desired space at the slowest walking speed, and will prevent the shank, even during fastest walking, from swinging too far backwards.

15 A further object of this invention is to provide a leg prosthesis having a control mechanism for the swinging motions of the leg, which mechanism will urge the shank, when bent backwards with respect to the thigh, into the outstretched leg position to be ready for the support of the load.

20 One object of the present invention is to apply my new control mechanism for the swinging motions of an artificial leg to a leg which is equipped with a pressure-controlled knee-joint brake.

25 Still another object of the invention is a device which will increase the braking effect of a conventional knee-joint brake.

30 In accordance with the present invention, the above indicated objects, as well as those objects which will hereinafter appear, are achieved by providing in an artificial leg, including a thigh and a shank, a resilient connection between the thigh and the shank which will control the swinging motion of the shank, and limit the swinging movement, first by counterbalancing the gravity which pulls the shank forward, or by even favoring a slightly bent position of the shank. The connection will become more effective during further bending up to a certain bending angle, preferably about 150°, and will exert a steadily increasing counterpressure upon continued bending. The counterpressure ceases on further forcible bending below a certain angle, preferably about 90°, and then causes bending.

35 40 45 With my present auxiliary braking mechanism applied to an artificial leg provided with a pressure-controlled knee-joint brake, as shown in my Patent 2,588,013, the slightly eccentric brake surface of the thigh produces an increasing friction with the braking surface of the shank, as the outstretched condition is approached.

50 In order that the present invention may be fully understood, illustrative embodiments are hereinafter described in detail, merely by way of example, and shown in the accompanying drawings wherein:

55 Fig. 1 is a fragmentary vertical section through an artificial leg embodying features of the invention, the leg being shown in outstretched condition;

Fig. 2 is a view similar to that of Fig. 1, but showing the prosthesis with its knee bent at an angle of 30° or 150°;

Fig. 3 illustrates still another condition of the leg, the knee being bent beyond 90°;

60 Fig. 4 illustrates a modified artificial leg; and
Fig. 5 illustrates a detail.

Referring to the drawings, and initially to Figs. 1 to 3, the knee end portion 1 of the thigh of an artificial leg has jointed thereto for pivotal movements a rod 2. This rod projects into a cavity in the calf of the shank 3 and is guided in an eye 4 of a guide 6 secured to the shank. Even with the thigh in its extreme angular position, the rod 2 cannot slide out of the eye 4. Above the eye 4, the rod 2 is provided with a flange 5. Between the guide 6 and the flange 5, there is a resilient member on the rod 2. While a rubber buffer 7 is shown as a resilient

member in the embodiment of the invention, selected for illustration, it will be clear that a spring or any other resilient means may be employed instead of the rubber buffer.

In the outstretched condition of the leg, the rubber buffer is so far away from the guide 6 that the thigh may be bent through approximately 30°, as shown in Fig. 2, or through a smaller or larger angle, depending on the arrangement, before the rubber buffer, upon further bending of the leg, will be compressed (see Fig. 3). Thus, a certain bending angle may be reached by a freely swinging pendulum movement without a braking action on the part of the resilient means 7. Only upon further bending occasioned, for instance, by faster walking, the buffer will be more or less strongly compressed and will finally resiliently limit the swinging movement, forcing the shank to reverse its movement.

Since it is desirable that the shank be not moved toward the outstretched condition by gravity, while the bending is between 160 and 180°, but that bending be favored, I provide, according to the invention, a tension element 8, such as a rubber band or a spring. Such a tension element extends, for instance, between the shank 3 and the rod 2 so as to force the thigh, by means of the link 9, to bend until the buffer 7 abuts against the guide 6, as shown in Fig. 2.

The rod 2 is linked to the knee portion 1 of the thigh so that with a bend of more than 90°, the point of connection moves to the other side of the center of rotation, as shown in Fig. 3. Then, the expansive forces of the buffer 7 will favor a still further bending of the thigh. This has the advantage that with the bearer being seated, the leg does not tend to stretch out under the influence of the resilient means.

The rod 2 is also acted upon by a brake which is preferably mounted on the guide 6. The pressure of a small brake shoe is adjusted by means of a screw.

In the embodiment shown in Fig. 4, the knee portion 1' of the thigh of an artificial leg is provided with cam means 20, and the shank 3' has jointed thereto a member 22 to guide a compression spring 24, and a support 26 for a roller 28. The spring bears at one of its ends upon the support 26 urging the support outwardly. The support is arranged to slide along the member 22. The roller 28 serves as a cam follower. The mechanism of Fig. 4 acts similarly to the swinging control mechanism of Figs. 1 to 3.

In Fig. 5, an auxiliary braking mechanism according to my invention is shown, which mechanism will help increase the braking effect of a knee-joint brake whenever the outstretched leg condition is approached or reached. To the rear end 10 of the brake-shoe 11 of a knee-joint brake, a member 12 is slidably mounted. This member abuts with its upper flange 13 against the rear side 14 of the brake lining 15. A flange 17 provided with a threaded hole 16 is secured to the brake-shoe 11, and a flange 18 is secured to the member 12. The hole 16 receives a screw-bolt 19. It will be understood that on rotating the head 30, the member 12 may be moved against the brake lining 15 to compress same and to increase its thickness.

It is believed that the construction and operation of the forms of the invention, which have been dealt with hereinbefore, and the many advantages thereof, will be understood from the foregoing detailed description. Some of the features of the invention are reviewed hereinafter.

As has been explained, the invention aims at the control of the swinging movements of a leg prosthesis. At the slowest walking speed, my control mechanism causes the shank to swing easily and naturally within the desired range, and during fastest walking, the shank is prevented from swinging too far backwards. In addition, my control mechanism urges the shank back into the outstretched leg position.

It will be apparent that while I have dealt primarily with a linkage between the thigh and the shank, articu-

lated both to the thigh and the shank, and provided with resilient means, many modifications of the control mechanism fall within the spirit of the invention. For instance, cam and cam follower means may be provided to cooperate together. The cam means are provided on either the thigh or the shank, and the cam follower means on the other leg section. The cam follower is urged by means of resilient means with more or less pressure toward the cam to produce greater or smaller friction during angular movements of the thigh and shank with respect to one another. The cam follower may be arranged to roll or to slide over the cam. It will be clear that by proper adjusting of the resilient means, retardation or acceleration of the swinging movements may be obtained. In order to influence the operation of the resilient connection, it is also possible to apply frictional forces at the articulations.

It will also be clear that the effect of my control mechanism may be varied through different positioning of the mechanism, depending on the location of the points of application of the forces involved.

With my swinging control mechanism applied to an artificial leg having a pressure-controlled knee-joint brake, I prefer to adjust the brake surface of a knee-joint brake in such a way that whenever the leg approaches or reaches the outstretched condition, an increased pressure is exerted on the corresponding slightly eccentric brake surface of the thigh. According to the invention, this is done by compressing a brake lining in either longitudinal and/or transverse direction and, thus, increasing its thickness. The device for compressing the brake lining is preferably mounted in the rear of the brake lining.

I claim:

1. Leg prosthesis including a thigh, a shank, a connection between the thigh and the shank, and elements resiliently affecting and controlling the relative angular position of the thigh and shank, said connection including a rod means, and a support, the rod means being articulated at one end to the thigh for pivotal movements, the support being carried by the shank and slidably receiving the rod means near the other end, the resilient elements including a tension member secured at one end to the shank, and at the other end to the rod means, and a body provided on the rod means intermediate the ends of the rod means, the resilient elements being provided to first counterbalance the gravity tending to move the shank forward, to become more effective during further bending of the shank through a bending angle up to approximately 150°, to produce a steadily increasing counterpressure upon continued bending, and to allow said counterpressure to cease on bending to an angle of approximately 90°.

2. In the prosthesis according to claim 1, an abutment carried by the rod means, said body being provided as a buffer in abutting relationship to the abutment, and in spaced relationship to the support in outstretched leg condition, the resilient body abutting against the support in a bent leg condition, and being adapted to become deformed on further bending.

3. In the prosthesis according to claim 1, provided with a pressure-controlled knee-joint brake including a brake-shoe brake lining and a thigh brake lining, a device movably arranged to be pressed against a side of the brake-shoe brake lining to thicken the latter brake lining and to increase the friction between the brake linings.

4. In the prosthesis according to claim 1, the rod means being jointed to the thigh at a point lying at one side of the center of rotation of the thigh and shank up to a rotation of approximately 90°, the said articulation point moving upon further rotation to the other side of the center of rotation.

5. Leg prosthesis including a thigh, a shank, and a connection between the thigh and the shank, said connection including cam means, a cam follower roller, a guide member, and a compression spring, the cam means being provided on the thigh, the guide member being articulated

to the shank, the cam follower roller being supported by the guide member to cooperate with the cam means, the compression spring being housed within the guide member to bear at one end against the cam follower roller.
